(57) **CLAIM**

The ornamental design for a combined detector host and blood pressure cuff, as shown and described.

DESCRIPTION

FIG. 1 is a front perspective view of a detector host showing our design.

FIG. 2 is a bottom rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front perspective view of a blood pressure cuff showing our design.

FIG. 10 is a bottom rear perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof.

FIG. 16 is a bottom plan view thereof.

FIG. 17 a front, top, and right side perspective view of a combination of the detector host shown in FIGS. 1-8 and the blood pressure cuff shown in FIGS. 9-16, wherein the detector host is attached to the blood pressure cuff.

FIG. 18 is a rear, bottom, and left side perspective view thereof.

FIG. 19 is a front elevation view thereof.

FIG. 20 is a rear elevation view thereof.

FIG. 21 is a left side elevation view thereof.

FIG. 22 is a right side elevation view thereof.

FIG. 23 is a top plan view thereof; and,

FIG. 24 is a bottom plan view thereof.
